ABSTRACT

A method for the production of a spark plug center electrode comprising the steps of preparing a plate for extrusion from a clad plate produced by bonding a corrosion-resistant metal plate and a good heat conducting metal plate together, and cold-extruding the plate for extrusion to a rod form.

METHOD OF PRODUCING SPARK PLUG CENTER ELECTRODE

BACKGROUND OF THE INVENTION

1. Field of the Invention

The present invention relates to improvements in a method for the production of a spark plug center electrode of the type in which the core member consisting of a good heat conducting metal such as copper is inserted into the central part of the covering member consisting of a corrosion-resistant metal such as nickel.

2. Description of the Prior Art

In a known method of producing a spark plug center electrode, a covering member is produced by boring a rod of corrosion-resistant metal such as nickel and then a rod-shaped core member consisting of a good heat conducting metal such as copper is inserted into and soldered to the covering member. A disadvantage of this prior art method is that since the bore for receiving the core member of good heat conducting metal is formed in the covering member of corrosion-resistant metal by the process of cutting, there is a problem from mass production point of view. Moreover, it is difficult to ensure a positive bonding between the core member and the covering member with the resultant instability in the production process.

SUMMARY OF THE INVENTION

To solve the foregoing problems, it is an object of the present invention to provide a method for the production of a spark plug center electrode comprising a first step of preparing a plate for extrusion from a clad plate formed by bonding a corrosion-resistant metal plate and a good heat conducting metal plate together, and a second step of shaping the plate for extrusion into a rod form by the process of cold-extrusion, whereby the method is well suited for mass production and the production process is also stabilized.

Since the method according to the present invention comprises a first step of preparing a plate for extrusion from a clad plate composed of a corrosion-resistant metal plate and a good heat conducting metal plate bonded together, and a second step of cold-extruding the plate for extrusion to a rod form, there is no need to count upon the corrosion-resistant metal plate and the good heat conducting metal plate being bonded together during the cold exclusion operation, and moreover there is no possibility that any foreign matters are included between the covering member of corrosion-resistant metal and the core member of good heat conducting metal and that air or the like is trapped between the two metals, thereby ensuring a very stable production process. Also since the plate for extrusion is prepared from the clad plate, the plate for extrusion is produced in a simple operation and moreover the core member can be covered with the covering member without requiring any cutting operation, thereby ensuring a higher mass production efficiency.

BRIEF DESCRIPTION OF THE DRAWING

FIG. 1 is a side view of a clad plate employed in the method of producing a spark plug center electrode according to the present invention.

FIGS. 2 and 3 are perspective views of plates for extrusion prepared from the clad plate shown in FIG. 1.

FIG. 4 is a fractional longitudinal sectional view of a cold extrusion die in which the plate of FIG. 2 or 3 may be inserted.

FIG. 5 is a longitudinal sectional view of a center electrode extruded by the cold extrusion die shown in FIG. 4.

DESCRIPTION OF THE PREFERRED EMBODIMENT

10 The present invention will now be explained with reference to an embodiment illustrated in the drawings. FIG. 1 illustrates a clad plate 3 formed by bonding a plate 1 of corrosion-resistant metal such as nickel to a plate 2 of good heat conducting metal such as copper. 15 While it is more economical to form the clad plate 3 by the process of cold or hot pressure welding, the clad plate 3 may also be formed by such means as soldering or explosion pressure welding. In the first step of the method of the embodiment, the clad plate 3 composed 20 of the corrosion-resistant metal plate 1 and the good heat conducting metal plate 2 is cut out by a press or the like into hexagonal columns to produce plates for extrusion 4 as shown in FIG. 2 or alternatively the clad plate 3 is cut into long strips of the material so that each 25 of the long strips is cut out into materials for extrusion 4 of square columnar shape as shown in FIG. 3.

If necessary, the corners of the hexagonal or square columnar plate for extrusion 4 may be removed.

In the second step, the plate for extrusion 4 prepared 30 in the first step is inserted in an extrusion die 5 of a cold extruding machine and pressure is then applied thereto by means of an extrusion punch 6 so that when a product is formed which comprises a cup-shaped covering member 7 consisting of the corrosion-resistant metal plate 1 and core member 8 consisting of the good heat conducting metal plate 2 and enclosed by the covering member 7, the core member 8 and the covering member 7 are firmly bonded to each other. With this cold extrusion of the extrusion plate material 4, if the hexagonal or square columnar extrusion plate is used, there 35 is almost no difference in the shape of the final product as compared with a cylindrical extrusion plate, and moreover by cutting out the hexagonal or square columnar extrusion plate material 4 from the clad plate 3, the loss in the material can be reduced considerably 40 as compared with the cylindrical extrusion plate material 4. Following the extrusion, if necessary, the extruded product is subjected to a finishing operation such as sizing to produce a finished center electrode of 45 any desired dimension which is then assembled into a spark plug.

We claim:

1. A method of producing a spark plug center electrode comprising a core member consisting of a good heat conducting metal and a corrosion-resistant metal enclosing the sparking-side end and the side portions of the core member, the method comprising the steps of preparing the extrusion plate material from a clad plate formed by bonding a corrosion-resistant metal plate and a good heat conducting metal plate together, cutting said extrusion plate material in a square columnar shape out of said clad plate, and cold-extruding said extrusion plate material to a rod form.

2. A method of producing a spark plug center electrode comprising a core member consisting of a good heat conducting metal and a corrosion-resistant metal enclosing the sparking side end and the side portions of

the core member, the method comprising the steps of preparing an extrusion plate material from a clad plate formed by bonding a corrosion-resistant metal plate and a good heat conducting metal plate together, cut-

ting said extrusion plate material in a hexagonal columnar shape out of said clad plate, and cold-extruding said extrusion plate material to a rod form.
